DESIGN FOR A MUCILAGE APPLICATOR UNIT

Arthur C. Werner, Lodi, Calif.

Application February 4, 1949, Serial No. 685

Term of patent 3½ years

(Cl. D74—10)

To all whom it may concern:

Be it known that I, Arthur C. Werner, a citizen of the United States, residing at Lodi, in the county of San Joaquin and State of California, have invented a new, original, and ornamental Design for a Mucilage Applicator Unit, of which the following is a specification, reference being had to the accompanying drawing, forming a part thereof.

Fig. 1 is a perspective view of a mucilage applicator unit, showing my new design.

Fig. 2 is an elevational view of the mucilage applicator unit with the parts separated and the base in section.

I claim:

The ornamental design for a mucilage applicator unit, as shown.

ARTHUR C. WERNER.
